UNITED STATES PATENT OFFICE

ALFRED MOLANDER, OF ST. PAUL, MINNESOTA

MINERAL CONCENTRATOR AND PROCESS

Application filed February 14, 1925. Serial No. 9,091.

My invention relates to mineral concentrators, and involves a series of precipitating actions and the use of steam, compressed air, certain oil formulas and water. The object 5 is to separate the finer mineral particles from any mass of ore and to further separate the waste materials from the ore in such manner as to reduce the waste and thereby increase the percentage of mineral content. This will 10 be readily understood for example in the handling of iron ore where the percentage of iron compared to the percentage of so called waste such, as rock, sand etc., must be comparatively high or up to certain standards 15 before it is acceptable at the smelters. The process I have will be further understood from the accompanying drawing, in which:—

Fig. 1 is an end elevation of the preferred 20 form of my concentrator machine, with the exterior driving means omitted, the major part of the end wall omitted to expose the main mechanisms.

Fig. 2 is a top view of the ore receiving 25 container in the upper part of the machine, some details being omitted.

Fig. 3 is a sectional elevation longitudinally of the machine about as on line 3—3 in 30 Fig. 1.

Fig. 4 is an enlarged top or plan view of 35 an end portion of one of the top plates 74 in Fig. 1 and Fig. 5 is an end elevation of said plate.

Fig. 6 is an enlarged sectional elevation, 40 as on line 6—6 of Fig. 2, of the baffle bar 23 used under the feed hopper 19.

Fig. 7 is an enlarged vertical fragmentary 45 section near one end of any of the three pairs of rollers 49 and adjacent parts, about as on line 7—7 in Fig. 3.

Fig. 8 is an end elevation of the concentrator showing mainly the various driving 50 means operated from a main drive shaft, and also different pipe lines required.

Fig. 9 is a detail elevation about as on line 55 9—9 in Fig. 7.

Fig. 10 is an enlarged fragmentary elevation of one corner of a vibrating screen 60 mounted below each feed hopper 19, about as on line 10—10 in Fig. 1.

Fig. 11 is a side elevation of the structure shown in Fig. 10.

I have illustrated a form of my device embodying the preferred construction in which there are two horizontally spaced, elevated 55 feed hoppers below each of which the materials go through a certain step in the process and after this step has taken place another step in the process takes place followed by a third step in the lower central part of the 60 machine with material fed in from below the mechanisms under the receiving hoppers.

Referring to the drawings by reference numerals, the main frame comprises at each end two pairs of uprights 15R and 15L the 65 top ends of which are suitably connected by horizontal end bars 16 and side bars 17. 18 in Fig. 1 is an end wall covering the upper part of the frame between each pair of uprights and may be extended across the entire 70 end of the frame as in Fig. 8 excepting of course necessary outlets and apertures hereinafter described. In Fig. 1 the near wall 18 is omitted from the left hand upper part and the entire lower end to expose the mechanisms it being understood that the mechanism in the upper right hand part is the same as that shown to the left and the products from both these mechanical units pass down through the lower central mechanism in the 75 80 final step of the process.

19 are the downwardly sloping walls of the feed hoppers, the lower ends of said walls being fixed in horizontal spaced relation to provide an outlet which may be closed by a 85 gate valve 21 (Fig. 1). Within the hopper and adjacent its outlet I provide a rotatable shaft 22 provided with radial fingers (Fig. 1) to facilitate an even feeding of ore out of the hopper from where it drops upon a baffle 90 bar 23 fixed longitudinally under said slot of the hopper. Said bar 23 is designed to form a series of aligned sections of triangular form, the sections having the apices 23A staggered alternately (see Figs. 2 and 6) for the purpose of spreading the dropped ore in about equal quantities from both sides of the bar onto a vibrator screen 24 suspended by links 25 in a horizontal plane under the hopper and longitudinally thereof. This screen is of 95 100

elongated, flattened prism form the quadrangular end of which is seen in Fig. 1 and its long side in Fig. 3, the latter showing more clearly the link suspension and an eccentric rod 26 pivotally connected at 26A to one of the links and with its eccentric mounted on a countershaft 27 mounted horizontally on the outside of the main frame and the rotation of which reciprocates the rod 26, links 25 and the entire screen 24 to provide a horizontal vibratory movement of the latter. The screen itself comprises a series of sets of bars 24A arranged transversely in spaced relation and each said bar being preferably of isosceles triangle form in cross section (see Fig. 10). The entire screen is immersed in water in a container, presently to be described, and the ore dropped upon its top layer of bars immediately is subject to an upward impelling force caused by the angular faces of the bars 24A between which bars its heavier particles gradually drop through the screen.

The first step in the treatment of ore will now be described, there being three distinct steps all told. It may be assumed that sulphide copper is to be put through the process. It will be understood that in this first step of the process the fine metal particles are recovered first and the coarser metal and rock particles are separated from the non-metal bearing and finer rock, the latter being passed off in this step of the process, as follows:

In the upper portion of each column of my machine is a container just below the feed hopper and comprising elongated side walls 46A, a hopper bottom 46 the lowest central part of the latter having a downwardly tapering outlet 46B terminating adjacent the contacting parts of two rubber faced rollers 49 (see Figs. 1 and 7). 31 are two troughs one at each side and adjacent the walls 46, also extending across the ends of the container (Fig. 2). 28 are two cold water pipes letting in water one at each side in the upper parts of walls 46A and 47 is a longitudinally arranged water pipe in the lower central part of the container and having outlets (not shown) in its upper side to eject water upwardly in the container, all three said water pipes coacting to keep the container full and the overflow passing out through the troughs 31 and their outlets 32 (Fig. 2). Below the screen 24 I suspend another screen 33 preferably wider and deeper than screen 24 and is suspended by links 34 adapted to be reciprocated in the same manner as screen 24 by suitable means such as an eccentric rod 35 pivotally connected with one of the links 34 and its eccentric 35A operated by a countershaft 36 rotatably mounted in bearings 37 on the outside of the frame (Figs. 1, 3 and 8). The shafts 27 and 36 are identical, one at each end of the machine, each extending horizontally across the upper end of the frame and connected with the respective

screen shaker rods 26 or 35. The shaft 22 within each hopper 19 extends beyond the end walls and carries a sprocket 38 in mesh with a worm 39 on shaft 27-36 for rotating shaft 22 (Fig. 8). Shafts 27 and 36 are each rotated by means of a pinion 40 meshing with a gear 41 suitably mounted on a shaft 42 carrying also another (bevel) gear 43 rotated by a large bevel gear 44 on the main drive shaft 45 (Fig. 8) suitably mounted longitudinally in the upper central part of the machine and operatively connected to any suitable source of power (not shown).

The rubber faced contacting rollers 49 are mounted on horizontal shafts 50 the ends of which extend through walls 18 and carry rotating means. These rollers are in constant frictional contact directly under the outlet 46B of the container and rotate inwardly and downwardly as indicated by arrows 51 (Figs. 1, 3 and 7). 52 are supplementary rollers each on a shaft 53 and preferably made of brass, the lower side of each contacting with the upper face part of a roller 49 and the upper side of each roller rotates in a semi-circular sleeve or bearing 46C formed integral with and on the lower side of the hopper bottom 46. The lower edges of the outlets 46B are permanently fixed adjacent the rubber rollers (see Fig. 7). 77 is a preferably brass plate or gasket on the inner side of wall 18, and the ends of the rollers 49 and 52 are made smooth to contact against said gasket. Thus is formed a watertight seal between said gaskets and the adjacent inwardly directed faces of the rollers 49 and 52.

Between the screens 24 and 33 I mount a suitable pipe frame comprising two longitudinal feed pipes 29 connected by a number of transversely arranged pipes 29B perforated as at 29A upwardly (see Fig. 1). Pipes 29 are fed by a suitably connected pipe line 30 outside the main frame (see Fig. 8). Through these pipes a suitable oil is forced with steam and compressed air and is discharged upwardly in the container where the oil vaporizes and causes instant formation of bubbles on the surface of the water for a purpose presently to be described.

In this first step of the process material is dropped from the hopper striking the baffle bar 22 and is distributed onto the vibrating screen 24. A large percentage of metal and rock will, because of its weight, precipitate downwardly through both screens 24 and 33 and be discharged between the rollers 49. The other percentage of materials will, because of its lighter weight, be held in suspension by the upwardly impelling contact of the slanting surfaces of the upper screen bars thus forcing the ore particles toward the surface. The effect of the rapidly vibrating screen and the upwardly rushing steam, oil vapor and compressed air from pipes 29B

charges the surface water with a mass of bubbles or foam which trap the metal particles. The continuous bubble formation moves upwardly and outwardly being guided or directed by the outside surfaces of the hopper walls 19 and said foam is removed by any suitable means (not shown). The waste or rock particles held in suspension by the upper screen are gradually moved or forced toward the sides, by the fresher materials coming up, into the unvibrated zone on each side of the screen where the water flowing in from pipes 28 carries said waste toward the ends of the hopper and is carried over the top edge of the walls 46A into the trough 31 as an overflow particularly at the ends of the hopper as indicated by arrows W in Fig. 3. If the lower screen is regulated to correct vibrating speed any waste which may have come through screen 24 will be held in suspension and gradually directed to the overflow as at W in Fig. 3, whereas the heavier particles precipitate through screen 33 to the rollers, it being understood that the upwardly directed currents of water from pipe 47 are not strong enough to prevent this latter precipitation of materials to the rollers.

54 is a horizontally disposed vertically adjustable, wedge shaped (in cross section) bar between the lower adjacent edges of the outlet 46B and the vertical adjustment of which regulates the feeding of ore between the rollers from the container. These rollers 49 are preferably faced with a soft but tough pump 35 rubber about one inch thick. The resilient nature of the rubber and the close contact of the rollers makes it practical to pass fine material, or what may be termed the solids fed down from the container, downwardly 40 and discharge from thence to the mechanism involved in the second step of my process. At the same time that the solids are thus discharged the water is squeezed back making it possible to operate what I call the second 45 flotation step in the process in practically clear water.

The wedge bar 54 is suspended by vertical end members 54A each having a horizontal outwardly directed tongue 54B extending 50 through a vertical slot 55 in the end wall and said tongue is engaged by vertically adjustable screws 56 in brackets 57 on the end wall and adapted to engage tongue 54B, one above and one below, for vertical adjustment 55 of members 54A and also, of course, the bar 54.

Each slot 55 must, of course, be closed to prevent escape of water and this may be done by extending member 54A to completely 60 cover it (not shown).

At the lower side of each roller 49 I provide a rotary brush 58 for removing all matter clinging to the roller by brushing it inwardly and allowing it to drop onto a hopper 65 59 with a longitudinal outlet 60 (see Fig. 1).

It will be readily understood that all solids or materials passed down from rollers 49 to hopper 59 are comparatively dry, having gone through the wringer-like action of the rollers. At this stage of the description it 70 will also be most readily seen that the first step of my process above described constitutes a primary flotation step by the bubble or foam forming action, separation of the finer rock and foreign matter from the heavier particles, precipitation of the latter and wringing the same through the rollers. 75

The second step in my process is another flotation process or action which takes place before the third and last step of my process. 80 The said second step will now be described:

The metal particles that can be raised off the surface of the water as in the first step, of my process, are limited to a certain weight and therefore do not include all the metal particles that will float, especially so if the water is clear when a greater percentage of metal not only floats but stays longer on the surface. 85

In this second step of my process the ore drops from hopper 59 onto a vibrating pan 61 suspended by an outer set of links 62 keyed on a rock shaft 63 and an inner set of vertically adjustable links 64, the pan being adjustably inclined inwardly and downwardly 90 toward the center of the machine. Shaft 63 is mounted in the frame parallel to the rollers 49 and is oscillated to vibrate the entire pan in a manner causing the ore on it to be moved toward its lower or discharge end, 95 said latter end of the pan normally in position dipping into the water of a large container in the lower part of the machine and presently to be described. Oil and water are dropped on the pan from a suitable feed pipe 76 (Fig. 1) connected with a suitable source by a pipe 65 (Fig. 8). The vibration of the pan and the running oil and water slides with the materials on the pan to its discharge end, the oil meantime forming a film which 100 raises the metal flakes to the top and the heavy ore is precipitated in the water of the lower container and said flaked metal moves directly into a V-shaped trough 67 which may also be termed a chute for carrying off the oil and flakes. This flotation step is 105 highly efficient inasmuch as the water is clear of rock matter at this point and the floating metal particles are readily recovered on the surface of the clear water in the lower container. It is evident that the coarser metals and rock particles will separate from the oil-sustained finer particles at the discharge end of the pan 61 and are precipitated in the water of the large container. At this 110 stage the third step of my process begins and will now be described.

The metal particles and rock particles precipitated, as just above described, drop downwardly through several inches of moving 115

water from each pan to another reciprocating screen, the frames of said screens being designated as 71R and 71L in Fig. 1 and each covered by a plate which I shall term the precipitation plate 74. Said plates are adjustably secured one above each screen 71R and 71L and in such a manner as to vibrate with it. Each plate is hinged at its inner edge and its other longitudinal edge is adjustable vertically, by means of screws 75, to set the plate at any desired slope toward the center of the machine.

The screens 71R and 71L are reciprocated longitudinally in suitable slides (not shown) by eccentric rods and eccentrics 72 operated by a shaft 73 mounted on the frame end wall 18 (see Figs. 1 and 8). Except for the precipitating plate the screens 71R and 71L are identical to screens 24 and 33.

The upper side of each precipitation plate 74 is fluted or grooved transversely as at 74A (Figs. 4 and 5). The vibration of the plate causes the slanting faces of the flutes to project upwardly practically all matter that falls upon it thus creating an upward impelling pressure. Correct speed of the screens and plates forces the waste matter into suspension and allows only particles that have a certain specific gravity to stay in the grooves or flutes of the plates 74. The third step of my process now being described takes place in a large central container arranged longitudinally and comprising two opposite ledges 68 sloping downwardly toward the center, one under each tray 61, the lower edge of each ledge 68 connected with a vertical wall 69 and the latter having each a centrally directed extension or bottom 70 terminating at the upper end of a central hopper-bottom 46C. This large container is similar to either of the upper containers but receives ore precipitated from the two horizontally spaced screens 71R and 71L, and the plates 74. All matter which stays in the grooves of the plates 74 will gradually move down the incline, being aided by streams of water directed inwardly and downwardly from a pipe 78 located adjacent the higher end of the plate. The lower half of each plate 74 is provided with a series of small holes 74B and narrow transverse slots 74C allowing the coarser and heavier metal particles to drop upon the screen below while the rock and sand or other matter in suspension, as above described, will drop over the lower edge of the plate and into a central trough 79 arranged longitudinally between the screens 71R and 71L and from which trough all said foreign matter is removed by flushing or other suitable means (not shown).

80 are vertically arranged gate valves in the trough. 81 are two horizontally arranged water supply pipes within the lower container to discharge fresh water and maintain any desired level of water. 47C is a central

water pipe adjacent the outlet of hopper bottom 46C and has upwardly directed outlets (not shown) for emitting streams of water the same as the pipe 47 in each of the upper containers. The concentrates in hopper bottom 46C are discharged therefrom in the same manner as from the upper containers and pass between rollers 49C separating the solids from the water, and dropping said solids into any suitable container as 82 in Fig. 75. 1. Said rollers 49C and all their adjacent co-operating parts are duplicates of the rollers and parts under each of the upper containers and said parts below the lower container are designated with corresponding 80 numbers and a suffix "C". There is also a feed regulating bar 54C adjacent the rollers 49C.

Fig. 8 illustrates suitable driving means and pipe lines, some of which have been already described.

45 is the main drive shaft having a bevel drive gear 44 which engages pinions 43, previously described, and also two opposite pinions 82R and 82L on horizontal counter-shafts 83R and 83L each of the latter having a bevel pinion 84 engaging a bevel gear 85 on one shaft 50 of each pair of rollers 49. Each of said pair of shafts 50 carries meshing gears 86 to properly rotate the rollers. 87 are pinions each meshing with a gear 86 and on the outer end of shaft 53 for rotating the rollers 52. The lower central set of rollers has a similar drive gear mechanism on a secondary countershaft 83X connected 100 with countershaft 83L by suitable means such as a drive chain 88 driven by a sprocket 89 on shaft 83L and driving a sprocket 89A on shaft 83X.

90 and 90A are a pair of chain sprockets 105 on shaft 83L driving by chains 91 and 91A respectively two small sprockets 92 and 92A rotating respectively an upper countershaft 93 and a lower one 93A, each of the latter having a bevel pinion 94 meshing with a pinion 95 mounted on the exposed outer end of each brush shaft 58.

The pans 61 are vibrated simultaneously by means of a connecting rod 96 pivotally secured to rocker arms 63A on the outer ends 115 of the shafts 63. Said rod is reciprocated by a vertical rocker arm 97 pivoted as at 97A. The lower end of arm 97 engages the rod and the upper end is engaged in a spiral groove 98A on a collar 98 fixed on counter-shaft 83R and which causes the arm 97 to oscillate in a vertical plane.

99 is a feed water pipe with suitable outlets to pipes 78, 81 and 47C in the main container.

It is necessary for a complete understanding of my process and machine to state in outline form its combination of flotation and precipitation principles. The process com- 120

prises the three steps described all taking place in one machine.

The first step.—Separating and recovering the light metal particles, in the upper container, from the coarser rock particles and from the heavier mineral bearing particles. The finer particles are carried up to the surface and carried off in the flotation or bubble formation described. The foreign matter and rock particles are kept in suspension and finally carried away to the waste overflow and the heavier particles precipitate in said upper containers is passed downwardly through the rollers.

The second step.—The oil treatment of the materials passed down from the first discharge rollers and which causes flotation of light values or particles that were too heavy for flotation by the air bubbles of the first step. This takes place on the vibrating pans where the material is precipitated on the surface of the fresh water in the lower container and the said light particles are carried off in the troughs. The remainder of the materials precipitate in the said water as described.

The third step.—The precipitation of materials in the fresh water of the large container to the precipitation plates, where the materials are further separated, the foreign matter and rocks being forced into suspension and carried away in the center trough while the values or minerals of greatest specific gravity are precipitated from the precipitation plates and through the lower screens, thence through the last rollers.

I wish to emphasize the fact that my machine and the process are practical for concentration of many different kinds of minerals or ores of various grades. Some grades of ore or materials handled must of course be handled or placed through my process at different rates of speed and consequently these and other conditions that may be present make it necessary that variable speeds of the main shaft are available. Also the volumes of oil, compressed air, steam and water may vary greatly. Speed regulating means for the main shaft or any of the secondary or minor mechanisms, directly or indirectly effecting all the mechanisms and valves for regulating means to control the flow of water etc., may of course be installed where necessary but all these things being old in the mechanical field I have omitted such regulating means to avoid unnecessary complicating of the drawings.

What I claim is:

1. A mineral concentrating process comprising a number of successive steps, the first step consisting of immersing ore in a quantity of moving water, charging said water with an upwardly directed foam and bubble forming element to raise and float the light metal particles of ore and separating said particles from the water as the heavier par-

ticles precipitate in the water; a second step consisting of removing the last mentioned heavy particles from the water and treating said particles with a suitable oily flotation element and discharging said oily mass on the surface of a volume of moving, clear water to float the fine metal particles by the action of the oil; and a third step comprising precipitation in said clear water of said heavier particles and suspending the waste particles therein by upwardly directed streams of water while the mineral bearing particles precipitate in the water and stratify.

2. In a mineral concentrator, an ore precipitating receptacle, water supply ducts for maintaining a predetermined level of moving water therein, a horizontally disposed vibrator frame in the receptacle and normally immersed in the water to contact with ore precipitated in the receptacle to project light particles of ore to the surface, a hopper-like bottom in the receptacle in which the heavier ore particles settle and stratify, an elongated narrow outlet in said hopper, a contacting means for discharging the heavy ore from said outlet while retaining the water in the receptacle, ducts within the receptacle having upwardly directed apertures to project a mixture of oil and vapor upwardly within the water to keep the precipitating ore particles in temporary suspension; said vibrator frame comprising an elongated prismatic frame with a series of vertically spaced layers of parallel bars of triangular form in cross section and having two upwardly directed angular faces, all said bars adapted to engage the ore precipitating in the receptacle to impel the ore upwardly but permitting heavier particles to precipitate between them to the bottom of the receptacle.

In testimony whereof I affix my signature.

ALFRED MOLANDER.
